[57] CLAIM

The ornamental design for a variable volume liquid dispensing closure, as shown and described.

DESCRIPTION

FIG. 1 is a side elevational view of a variable volume liquid dispensing closure showing our new design;

FIG. 2 is a front elevational view;

FIG. 3 is a rear elevational view;

FIG. 4 is a sectional view taken on the line 4—4 of FIG. 1;

FIG. 5 is a top plan view;

FIG. 6 is a side elevational view showing a modified form of our new design wherein the pouring lip is absent; and

FIG. 7 is a front elevational view of the modified form of our new design shown in FIG. 6.

The broken line showing of a portion of a bottle in FIGS. 1, 2 and 7 is for illustrative purpose only.
